UNITED STATES PATENT OFFICE.

JOHN F. BEANS, OF CANTON, OHIO, ASSIGNOR TO THE BEANS SPRING COMPANY, OF MASSILLON, OHIO, A CORPORATION OF OHIO.

SPRING FORMING AND QUENCHING MACHINE.

Application filed October 14, 1921. Serial No. 507,674.

To all whom it may concern:

Be it known that I, JOHN F. BEANS, a citizen of the United States, residing at Canton, in the county of Stark and State of Ohio, have invented a new and useful Spring Forming and Quenching Machine, of which the following is a specification.

This invention relates to improvements in machines for forming and quenching springs such as are used upon automobiles and similar vehicles.

In the manufacture of springs of this character, each spring is formed of a plurality of flat leaves, each leaf being formed from a flat bar of steel bent to a predetermined curvature and hardened to retain the exact curvature.

It is necessary that the several leaves forming a complete spring be bent exactly and uniformly and that all leaves of the spring be uniformly and evenly hardened in order that they retain the proper shape.

The objects of the invention are to provide a machine for forming and quenching springs in which the leaves may be quickly and uniformly formed and hardened.

The above and other objects may be attained by providing a quenching tank with which is mounted a pair of upright guides extending to a point considerably above the tank, a pair of forming jaws being slidably mounted upon said uprights, the lower jaw being supported by counter weights, the upper jaw having a limited movement with reference to the lower jaw, being operated by an air cylinder controlled by the operator, whereby the jaws may be raised from the tank and opened to permit the removal of a finished spring and the placing of a new blank between the jaws after which the jaws are closed and moved downwardly into the tank to quench the spring.

The invention thus set forth in general terms is illustrated in the accompanying drawings, in which—

Figure 1 is a side elevation of a spring forming and quenching machine embodying the invention, the quenching tank being shown in section;

Fig. 2, a section on the line II—II, Fig. 1;

Fig. 3, a section on the line III—III,

Fig. 4;

Fig. 4, a section on the line IV—IV, Fig.

3; and

Fig. 5, a vertical sectional view through

the air cylinder and a portion of the air pipe.

Similar numerals of reference indicate corresponding parts throughout the drawings.

Referring to the construction illustrated in the drawings, a single unit is shown adapted to form and quench one spring leaf at a time; but in the practical application of the invention it has been found advantageous to arrange a plurality of these units in a tank in position to be successively operated by one workman, as each spring should be left in the oil a sufficient time to be properly cooled and tempered before being removed from the forming jaws.

The oil tank is illustrated at 1, oil being conveyed thereto through the pipe 2 which extends downwardly to a point near the bottom of the tank as shown at 3, an overflow outlet being provided at 4. By this means the oil level is maintained at the height of the overflow 4.

The spaced, upright guides 5 are supported upon the longitudinal channel iron 6 spaced slightly above the floor of the tank and are connected at their upper extremities by the longitudinally disposed rod 7 which supports, intermediate its extremities, the collar 8 in which the air cylinder 9 is mounted, tie rods 10 extending from the upper end of the cylinder to the upper extremities of the uprights 5 for the purpose of bracing the cylinder in upright position.

The forming head comprises the lower jaw 11 and the upper jaw 12, each of which is provided at opposite ends with a bearing portion 13, slidably mounted upon the uprights 5 upon which the jaws are independently movable. Each of these jaws is preferably of channel form as best shown in Fig. 4, bolts 14 being carried by the lower flange of the upper jaw and extending loosely through apertures 15 in the upper flange of the lower jaw, a nut 16 being placed upon the lower end of each bolt. With this construction, the upper jaw has a relative movement with respect to the lower jaw, which is limited by means of the nuts 16.

Cables 17 are connected at one end to the extremities of the lower jaw as at 19 and pass upwardly over the pulleys 20 which are journaled upon the extremities of the tie rod, the other extremities of said cables supporting the counter weights 21 which are sus-

pended within the tank. A pair of upright stop members 22 are supported upon the channel 6 and limit the downward movement of the lower jaw.

5 The cylinder 9 has a piston 23 therein provided with the oppositely disposed leather washers 24, the piston rod 25 being connected at its lower end to the bracket 26 which supports the upper jaw 12.

10 The curved plate 27 is supported upon one side of the lower jaw by means of the angles 28, guide lugs 29 being provided with the inturned under portions 30 which are secured to the under surface of the plate 27 upon its outer edge, similar guide lugs 31 being provided along the inner edge of said plate and preferably staggered with relation to the lugs 29. This forms an arcuate seat for the blank 32 from which the spring leaf 20 is formed.

15 The upper jaw is provided with a plurality of coacting fingers 33 arranged in arcuate position, each being provided with the angular attaching flange 34 having a slot 35 through which the bolts 36 are located, by means of which the fingers may be adjusted radially upon said upper jaw to accommodate spring leaves of different thickness.

20 Air is supplied to the cylinder through the pipe 37 which leads from any suitable source of compressed air and communicates with the lower end of the cylinder as at 38, a valve 39 controlling the entrance to the cylinder at this point, while a similar valve 40 35 controls the entrance to the upper end of the cylinder.

25 Each of these valves comprises a rotary plug 41 having a transverse bore 42 therethrough and a longitudinal groove 43 in one side. A lever 44 is connected to the stem 45 of the upper valve and a similar lever 46 is connected to the stem 47 of the lower valve. A link 48 is pivotally connected to the outer extremities of the levers 44 and 46 and one 30 extremity of the link 49 is pivotally connected to the link 48 intermediate the ends thereof, the other extremity of the link 49 being pivotally connected as at 50 to the extremity of a lever 51 which is pivoted at 55 35 52 in a bracket 53 depending from the tie rod 7, the other end of said lever being pivotally connected as at 53 to the upper end of the link 54, and pivoted at its lower end to the inner extremity of the operating lever 55 which is pivoted upon the lug 56.

40 In operating the device, the lever 55 is moved to open the lower valve 39 and close the upper valve 40, allowing the air in the upper end of the cylinder to exhaust through the groove 43 in the upper valve, air being admitted to the lower end of the cylinder, raising the piston and through the piston rod, raising the upper jaw until the nuts 16 upon the bolts 14 engage the lower jaw when 45 the lower jaw will be raised together with

the upper jaw, the forming head being moved out of the oil in the open position as indicated in Fig. 3.

45 A heated blank is then placed upon the curved plate 27 of the lower jaw, between the guide lugs 29 and 31 and the operating lever 55 moved in the opposite direction, moving the valves 39 and 40 into the position shown in Fig. 5, the upper valve being opened, admitting air to the upper end of 50 the cylinder and forcing the piston down, the lower valve being closed and allowing the air in the lower end of the cylinder to exhaust through the groove 43 thereof, the upper jaw being lowered into engagement 55 with the lower jaw, bending the hot blank into shape between the jaws, the head being lowered into the oil until the lower jaw 11 engages the stops 22, the piston holding the upper jaw down upon the lower jaw as 60 shown in Fig. 1, clamping the heated blank between the forming fingers 33 and the curved plate 27, clamping the blank in the required form and holding the same clamped in this position beneath the oil.

65 After the formed spring has been held in the oil in this position for the required time, the lever 55 is again operated to raise and open the forming head when the finished spring may be lifted therefrom and a new 70 heated blank placed upon the lower jaw, after which the forming head is again lowered into the oil as above described.

75 I claim:—

1. A spring forming and quenching machine including a tank containing quenching liquid, a forming head comprising upper and lower jaws mounted for vertical movement into and out of said tank, means connected to the upper jaw for raising and lowering the same, means for suspending the lower jaw from the upper jaw and means independent of the upper jaw for counterbalancing the lower jaw.

80 100. 2. A spring forming and quenching machine including a tank containing quenching liquid, a forming head comprising upper and lower jaws mounted for vertical movement into and out of said tank, means connected to the upper jaw for raising and 105 lowering the same, depending rods upon the upper jaw, means upon said rods for engaging the lower jaw to raise the same with the upper jaw after the upper jaw has been raised a predetermined distance, means for 110 limiting the downward movement of the lower jaw and means independent of the upper jaw for counterbalancing the lower jaw.

85 115. 3. A spring forming and quenching machine including a tank containing quenching liquid, a forming head comprising upper and lower jaws mounted for vertical movement into and out of said tank, means connected to the upper jaw for raising and 120 125 lowering the same, depending rods upon the upper jaw, means upon said rods for engaging the lower jaw to raise the same with the upper jaw after the upper jaw has been raised a predetermined distance, means for limiting the downward movement of the lower jaw and means independent of the upper jaw for counterbalancing the lower jaw.

90 130.

lowering the same, depending rods upon the upper jaw and means upon said rods for engaging the lower jaw to raise the same with the upper jaw after the upper jaw has been raised a predetermined distance.

4. A spring forming and quenching machine including a tank containing quenching liquid, a forming head comprising upper and lower jaws mounted for vertical movement into and out of said tank, means connected to the upper jaw for raising and lowering the same, depending rods upon the upper jaw and means upon said rods for engaging the lower jaw to raise the same with the upper jaw after the upper jaw has been raised a predetermined distance, and means for limiting the downward movement of the lower jaw.

5. A spring forming and quenching machine including a tank containing quenching liquid, a forming head comprising upper and lower jaws mounted for vertical movement into and out of said tank, means connected to the upper jaw for raising and lowering the same, depending rods upon the upper jaw and means upon said rods for engaging the lower jaw to raise the same with the upper jaw after the upper jaw has been raised a predetermined distance, and means for counter-balancing the lower jaw.

6. A spring forming and quenching machine including a tank containing quenching liquid, a forming head comprising upper and lower jaws mounted for vertical movement into and out of said tank, means connected to the upper jaw for raising and lowering the same, depending rods upon the upper jaw and means upon said rods for engaging the lower jaw to raise the same with the upper jaw after the upper jaw has been raised a predetermined distance, and means for counter-balancing the lower jaw and means for limiting the downward movement of the lower jaw.

45 7. A spring forming and quenching machine including a quenching tank, vertical guide members extending into the tank, a

pair of jaws slidably mounted upon the guide members, a flange upon the lower jaw provided with apertures, depending rods upon the upper jaw extending through said apertures, and provided with means at their lower ends to engage the flange upon the lower jaw, means for limiting the downward movement of the lower jaw and means for raising and lowering the upper jaw.

8. A spring forming and quenching machine including a quenching tank, vertical guide members extending into the tank, a pair of jaws slidably mounted upon the guide members, a flange upon the lower jaw provided with apertures, depending rods upon the upper jaw extending through said apertures, and provided with means at their lower ends to engage the flange upon the lower jaw, means for limiting the downward movement of the lower jaw, a vertical cylinder mounted above the upper jaw, a piston in the cylinder connected to the upper jaw and means for admitting fluid to either end of the cylinder to raise or lower the piston.

9. A spring forming and quenching machine including a quenching tank, vertical guide members extending into the tank, a pair of jaws slidably mounted upon the guide members, a flange upon the lower jaw provided with apertures, depending rods upon the upper jaw extending through said apertures, and provided with means at their lower ends to engage the flange upon the lower jaw, means for limiting the downward movement of the lower jaw, a vertical cylinder mounted above the upper jaw, a piston in the cylinder connected to the upper jaw, a fluid line connected to each end of the cylinder, a valve in said fluid line at each end of the cylinder, and means for automatically opening either valve and moving the other valve to exhaust fluid from the adjacent end of the cylinder.

In testimony that I claim the above, I have hereunto subscribed my name.

JOHN F. BEANS.
